UNITED STATES PATENT OFFICE.

EDWIN R. CLOUGH AND FRANKLIN JONES, OF LEBANON, MISSOURI.

FIRE-KINDLER.

SPECIFICATION forming part of Letters Patent No. 397,696, dated February 12, 1889.

Application filed May 26, 1888. Serial No. 275,191. (No model.)

To all whom it may concern:

Be it known that we, EDWIN R. CLOUGH and FRANKLIN JONES, citizens of the United States, residents of Lebanon, in the county of 5 Laclede and State of Missouri, have invented certain new and useful Improvements in Fire-Kindlers; and we do declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 Figure 1 of the drawings is a representation of this invention and is a perspective view. Fig. 2 is a vertical section, the handle being broken off. Fig. 3 is a cross-section on line x x , Fig. 2.

20 The invention relates to improvements in fire-kindlers; and it consists in the construction and novel combination of parts, as hereinafter set forth.

The object of the invention is to provide a 25 fire-kindler of an absorbent indestructible character, so that it may be used an indefinite number of times for starting a fire.

Referring to the drawings, A designates the 30 coiled-wire casing, the coils of which lie in close contact one upon the other.

B shows the similar wire end walls, having the annular flanged edge a , adapted to fit closely over the end coils of the casing A, as shown, and perforations b are provided in the

end walls for the passage of the wires C of 35 the handle. The handle-wire is bent centrally, as at c , and passes upwardly within the casing and out through the upper end wall, where it is twisted, as shown at d , and provided with a ring, e , for convenience of 40 withdrawing the device from the fire with a stick or poker.

D designates an oil-chamber located centrally within the outer casing, and provided with openings f through its walls to admit the 45 oil which passes through the packing E. The packing E fills all the space between the outer casing and the oil-chamber, and preferably consists of asbestos and clay mixed in proper proportions.

We do not confine ourselves, however, to asbestos and clay, as other absorbent non-destructible material may be used.

Having described our invention, what we 55 claim is—

A fire-kindler composed of the oil-chamber, located centrally and having the openings f , the absorbent packing completely surrounding said chamber, the outer casing; and the handle, substantially as specified.

60 In testimony whereof we affix our signatures in presence of two witnesses.

EDWIN R. CLOUGH.
FRANKLIN JONES.
